UNITED STATES PATENT OFFICE.

ABRAHAM MAX HOLTZMAN, OF BROOKLYN, NEW YORK.

SOLE-STITCHING MACHINE.

1,347,038.

Specification of Letters Patent.

Patented July 20, 1920.

Application filed December 22, 1917, Serial No. 208,343. Renewed March 13, 1920. Serial No. 365,659.

To all whom it may concern:

Be it known that I, ABRAHAM MAX HOLTZMAN, a citizen of the United States, and resident of borough of Brooklyn, county of 5 Kings, city and State of New York, (whose post-office address is 187 Osborn St., Brooklyn, New York,) pray that Letters Patent may be granted to me for the Improvement in Sole-Stitching Machines, of which the 10 following is a specification.

This device has for its principal objects the provision of means for operating a sole stitching machine by foot power. It has an advantage in this regard not found in 15 other machines in that the operator is in front of the machine and in a seated position.

This machine operating by the applied weight of the operator may be used with 20 material heavier or thicker than it is possible with a hand operated machine. Its work will also be found to be more even than that of the hand operated machine and as I provide means which will allow the 25 shoe to be turned through an almost complete circle it is quite obvious that the work of stitching a sole may be performed as a continuous and rapid operation.

The construction of my device and the 30 means for operating it will be set forth as the specification progresses.

The following is what I consider a good means of carrying out this invention and,

The accompanying drawings form a part 35 of this specification in which:

Figure 1 shows a plan view of my machine and,

Fig. 2 an elevation thereof.

Similar reference numerals indicate like 40 parts in all the figures where they appear.

My machine is constructed upon a portion which may be termed a table, and this table is indicated at 1,

45 Under the table 1, I arrange a plurality of legs or supports 2 and 3, the table 1 and the legs or supports 2 and 3 may and should be formed from cast iron.

50 Into the table and at one side of the center thereof I produce a recess 4, which will be later described or referred to.

In describing the operation and construction of my device I will commence with the power mechanism and continue throughout

the power transmission and the stitching 55 devices, in this way I hope to preserve a continuity which may be readily followed.

Upon a bar 5, arranged low down between the legs 2 and 3 I place a treadle which is free to move upon the bar 5, a 60 rod 7 connected by a ball and socket 8 to the treadle is also connected to a crank 9 upon a shaft which supports the driving wheel 10. A ball and socket 11 serves as the connection between the rod 7 and the 65 crank 9 and it will be noted that I provide a counter weight 12 in the driving wheel 10 at the side opposite to that toward which the crank 9 extends.

A belt 13 passing over the driving wheel 70 10 also passes over a driven wheel 14 and the wheel 14 is secured to a shaft 15 having a crank 16.

A rod 17 operable upon the crank 16 connects with the needle bar lever 18 and 75 by the rotation of the crank 16 the rod 17 reciprocates the needle lever 18.

A pin 19 extending through the lever 18 is secured to the needle bar 20 and the movement of the lever 18 will cause the 80 needle bar 20 to be reciprocated.

A block 21, secured upon the rod 17 has a projection passing into the table which projection operates the shuttle mechanism.

The shuttle and shuttle movement and 85 the needle and thread feeding mechanism are similar to those employed upon machines such as that shown in the patent to Soens, Patent Number 1,215,733, and need not therefore be described in detail.

I have however eliminated certain of the 90 parts of the Gritzner machine and have accordingly simplified the construction and operation of machines of this type, and I call particular attention to the arrangement 95 of the driving mechanism and its connection with the needle bar and shuttle.

Modifications in the drive and in other parts may be made within the scope of the appended claims without departing from 100 the principle or sacrificing the advantages of this invention.

Having carefully and fully described my invention what I claim and desire to secure by Letters Patent is:—

1. A sole stitching machine having a needle bar, a lever for operating said bar, a rod connected to said lever a driving means

for reciprocating said rod and an adjustable projection movable upon said rod for operating the bobbin.

2. A sole stitching machine having a needle bar, a lever for operating said bar, a rod connected to said lever, a crank for operating said rod, a projection adjustable upon said rod for operating the bobbin and a foot pedal, and a plurality of wheels connected therewith for operating said crank, said rod and said lever.

3. In a device of the character described

a foot pedal, a counter balanced driving wheel, a rod between said pedal and said driving wheel and having a ball and socket connection with said pedal and said wheel, a driven wheel, a crank connected therewith and a rod from said crank to the needle operating device and an adjustable projection upon said rod for operating the bobbin. 15 20

Signed at New York city, in the county of New York and State of New York, this 29 day of November, 1917.

ABRAHAM MAX HOLTZMAN.
